Attorneys

UNITED STATES PATENT OFFICE.

JAMES F. SYRETT, OF BALTIMORE, MARYLAND.

DUST SHIELD.

1,424,324.

Specification of Letters Patent. Patented Aug. 1, 1922.

Application filed July 10, 1920. Serial No. 395,347.

To all whom it may concern:

Be it known that I, JAMES F. SYRETT, a citizen of the United States, residing at Baltimore, in the county of Baltimore and

5 State of Maryland, have invented certain new and useful Improvements in Dust Shields, of which the following is a specification.

This invention relates to a dust shield for 10 covering and protecting portières, curtains or the like.

An important object of the invention is 15 the provision of a portière dust shield having a sheet, cloth or other similar protecting means suspended therefrom, and which is supported from a door or window casing in such manner as to cover and protect the portières or curtains thereon from dust or other substance which might injure the 20 portières or curtains.

A further object is the provision of a dust 25 shield of the above described character formed of different sections so as to permit its use upon various sized window or door casings, and which can be folded into a relatively small and compact size for convenience in handling.

Other objects and advantages will be apparent during the course of the following 30 detailed description. In the accompanying drawings forming a part of this specification and in which like reference characters designate like parts throughout the same.

Figure 1 is a front elevation of the portière dust shield supported from a window casing, and covering the portière thereon, to protect the same from dust or other foreign substance.

Figure 2 is a side elevation of the dust 40 shield supporting means in a folded position.

Figure 3 is a fragmentary sectional view of a portion of the device.

Figure 4 is an end elevation of the dust 45 shield supporting means, when in a folded position.

In the drawings, wherein for the purpose of illustration is shown a preferred embodiment of my invention, the letter A designates a window or door casing having the curtain or portière B suspended therefrom in any suitable manner. The supporting bar C is so arranged and suspended from the casing A by hooks D or other approved means in such manner that a dust shield E of any flexible material such as a sheet,

cheese cloth or the like is supported therefrom by clamps F to cover and protect the curtains or portières from dust or other foreign substance.

The supporting bar C is preferably constructed of two or more foldable sections 10 and 11, which are foldably connected by a hinge 12 or the like. The leaves of the hinge 12 are preferably countersunk in the faces 60 of the sections 10 and 11 in such manner that the abutting faces of the sections 10 and 11 will fit closely together when the supporting bar is in a folded position. The section 10 of the supporting bar C is provided upon an end thereof with a projection 13 adapted to ride upon an extending edge 14 of the clip 15 which is securely fastened to the end of the section 11, and adapted to seat itself within an aperture in the extension 14 in such manner as to lock the sections of the supporting bar in a folded position, as clearly shown in Figure 2 of the drawings.

When the supporting bar C is in an extended position and it is desired to use the same upon a relatively wide window or door, it is supported upon or from the same by the hooks D which are upon the upper surface thereof and engaged therein in any 80 suitable manner such as by screw threads or the like. It is preferred that the hooked ends 20 be provided with the pointed extensions 21 for firmly biting into the window casing and effectively support the device 90 therefrom.

The clamps F while firmly and securely holding the dust shield E will yet permit its removal therefrom by merely exerting a pull upon the dust shield E. It is preferably of 95 the type employing jaws 23 and 24 which have their gripping ends forced tight together by spiral springs 25, in such manner as to securely grip the dust shield or other article which is to be suspended from 100 the supporting bar C. They are arranged upon a longitudinal edge of the supporting bar C in such manner that the dust cloth E is evenly suspended therefrom. They are preferably individually clamped to the supporting bar C by a wire band 26 extending through the spiral spring 25, and having their projecting ends 27 and 28 threaded laterally through apertures in the bar C and twisted together as at 29 to securely fasten 110 the clamp to the supporting bar. The twist 29 is preferably folded over and seated with-

in a recess 30 in an edge of the bar C. The recess 30 may be filled with sealing wax or the like to cover up the end 29 in order that it will not catch upon the portières when 5 using the device.

It is to be noted that either of the sections 10 or 11 form in themselves a complete means for suspending the dust cloth E over a relatively narrow door way or window 10 casing.

The hook D and clamp F are so arranged upon the sections 10 and 11 of the supporting bar C that they will not interfere with folding of the different sections upon each 15 other in any way.

The usual procedure is first to evenly arrange the dust shield upon the supporting bar C by the clamps F, and then to lift it bodily and support it from the window casing A by the hooks D as is clearly shown in 20 Figure 1 of the drawing.

It is to be understood that the form of my invention herewith shown and described is to be taken as a preferred example of the 25 same and that various changes in the shape, size and arrangement of parts may be made without departing from the spirit of the invention or the scope of the subjoined claims.

I claim:

30 1. In a portière dust shield, the combination, of a supporting bar comprising a pair of sections hingedly connected midway of its length, a dust shield, and means carried by each of said supporting bar sections for 35 detachably clamping said dust shield thereto.

2. In a device of the character described, a shield supporting bar comprising a pair of sections hingedly connected for folding to decrease its length, and means carried upon the free ends of the sections for locking the supporting bar in folded 40 position.

45 3. A supporting device comprising in combination a supporting bar including a

pair of sections hingedly connected on their ends for folding purposes, and clamps on each of said bars, said clamps on one section staggeredly disposed with respect to the clamps on said other section when the sections are folded upon each other.

4. In a device of the character described, a shield supporting bar comprising a pair of sections hingedly connected for folding to decrease its length, and means carried by each of said sections for supporting either of the sections independent of the other section.

5. In a supporting device, the combination of a foldable supporting bar comprising hingedly connected sections, and clamps arranged upon a longitudinal edge thereof in such manner as to permit ready folding of the supporting bar.

6. In a portière dust shield, the combination with a casing and a curtain hanging therefrom, of a supporting bar comprising a pair of sections hingedly connected for folding to decrease its length, a dust shield, clamps arranged upon each of said sections 70 for detachably engaging and supporting said dust shield, and means for supporting said supporting bar from the casing in such manner that the dust shield overlies the portière for protection thereof.

7. In a portière dust shield, the combination with a casing and a curtain hanging therefrom, of a foldable supporting bar comprising hingedly connected sections, a dust shield, clamps arranged upon the longitudinal edge of each section for detachably engaging and supporting said dust shield, and means arranged upon each of said sections of the supporting bar whereby either of said sections can be supported from the 85 casing in such manner that the dust shield will cover and protect the portière independent of the other section.

JAMES F. SYRETT.
